UNITED STATES PATENT OFFICE.

LINN BENTLEY, OF COLUMBUS, OHIO, ASSIGNOR OF ONE-HALF TO LOUIS F. FIESER, OF COLUMBUS, OHIO.

BLAST-FURNACE.

SPECIFICATION forming part of Letters Patent No. 718,945, dated January 20, 1903.

Application filed September 9, 1902, Serial No. 122,651. (No model.)

To all whom it may concern:

Be it known that I, LINN BENTLEY, a citizen of the United States, residing at Columbus, in the county of Franklin and State of 5 Ohio, have invented certain new and useful Improvements in Blast-Furnaces; and I do hereby declare the following to be a full, clear, and exact description of the invention, such as will enable others skilled in the art to which 10 it appertains to make and use the same.

In most iron ores there is a considerable quantity of fine dust or particles of ore deemed to contain the best and purer metal, and heretofore in the process of reducing ore 15 in a blast-furnace a large proportion of this dust has been blown out through the downtake, accumulating in and choking the flues to such an extent that it has been necessary to shut down the furnace at frequent intervals 20 to remove the accumulation. This accumulation is often lost or wasted, because when it is added to a charge the ordinary quantity of dust is augmented and the trouble in the flues aggravated.

25 The object of my invention therefore is to provide an improved construction of gas-flue or downtake that will prevent to a great extent, if not entirely, the escape of the ore particles through the downtake.

30 In my improvements the downtake leads first upward from the top of the furnace and then downward, so that there shall be a tendency of the ore particles to fall by their own weight back into the furnace, where they will 35 be reduced along with the rest of the charge.

The invention also consists in providing the upwardly-leading part of the downtake-flue with substantially horizontally-extending obstructions or baffles, against which the ore 40 particles strike and are deprived of their momentum. The invention also consists in providing a "bleeder" directly above and in line with the axis of the upwardly-directed part of the downtake, so that the ore particles rising in it will fall back into the furnace through the said upwardly-leading portion.

The invention further consists in a peculiar construction of dust-catcher whereby most of the metallic and other dust that does 45 get around the bend in the top of the flue

may be detained and removed, all as herein-after particularly set forth and claimed.

In the accompanying drawings, showing one embodiment of the invention, Figure 1 is a central vertical sectional view. Fig. 2 55 is a plan of the dust-trap from the plane xx , Fig. 1; and Fig. 3 is a horizontal sectional view on the line yy , Fig. 1, looking down.

1 designates the blast-furnace, which is of any ordinary construction and need not be 60 described in detail.

2 designates the flue for carrying off the gases and has commonly been called the "downtake." Instead of carrying the flue downward from the top of the furnace I propose to first build it upward, as indicated at 2^a, and then downward. In this upwardly-leading portion 2^a I construct projections or baffles 2^b, preferably having their upper sides inclined, as indicated at 2^{bb}, so that particles 70 dropping or lodging thereon shall tend to roll off and fall back into the furnace.

3 designates a valved vent or bleeder to let out gas should the pressure become too high for safety. This bleeder I locate above the 75 upwardly-leading part of the downtake, so that particles of dust entering or lodging therein shall fall back into the flue and furnace.

The dust-trap comprises a chamber 4, into 80 which the upper end of the downtake discharges, the discharging end of the downtake being shown to be somewhat enlarged, but of smaller diameter than the diameter of chamber 4, so that the branch flues 2^c 2^c, forming 85 a continuation of the downtake, can lead upward out of the upper end of the chamber 4. Thus it will be observed that the discharging end of the flue 2 is practically in the same horizontal plane as the induction end of the 90 flues 2^c 2^c, and particles dropping into the trap 4 can hardly be carried upward through the flues 2^c 2^c. The lower end of the dust-trap is provided with a bell-valve 4^a, which may be operated at any time to discharge the 95 accumulation in the trap. The flues 2^c 2^c communicate or discharge into the ground or other flues 2^d, and the gases from the furnace may be conveyed to any place where it may be desired to utilize them—for example, 100

as fuel for stoves or boilers. The flue 2 can also be provided with a safety-valve 5 to give vent in case of explosion in that part of the downtake. With this construction it will be observed that the valuable metallized dust which has heretofore been wasted is saved and much annoyance and loss of time due to choking of flues avoided.

What I claim, and desire to secure by Letters Patent, is—

1. In a blast-furnace, a downtake, an upwardly-leading portion therein, and horizontally-extending projections on the inner side of said upwardly-leading portion to obstruct the passage of the dust particles through said upwardly-leading portion.
2. In a blast-furnace, a downtake, an upwardly-leading portion therein and dust-obstructing projections on the inner side of said upwardly-leading portion having inwardly-inclined upper sides and horizontal lower sides.
3. In a blast-furnace, the combination of a downtake, a dust-trap connected therewith

comprising a cylindrical portion of greater diameter than the inlet of the downtake thereto, and outlet-flues from the top of said cylindrical portion having their outlet ends lying in substantially the same horizontal plane as the inlet end of the downtake. 25

4. In a blast-furnace, a downtake, an upwardly-leading portion therein having interior projections or dust-baffles, a dust-trap in said downtake, and outlets from said dust-trap having their terminals lying in substantially the same horizontal plane as the inlet from the downtake. 30

5. In a blast-furnace, a downtake, an upwardly-leading portion therein provided with dust-obstructing projections, and a bleeder or explosion-valve located in line with the axis of said upwardly-leading portion. 35

In testimony whereof I affix my signature in presence of two witnesses.

LINN BENTLEY.
